UNITED STATES PATENT OFFICE.

THURE E. DAHL, OF NEW YORK, N. Y.

DESIGN FOR A BODY PLATE FOR ELECTRIC FIXTURES.

60,901.

Specification for Design. Patented Apr. 25, 1922.

Application filed May 31, 1921. Serial No. 473,930. Term of patent 3½ years.

To all whom it may concern:

Be it known that I, THURE E. DAHL, a subject of the King of Sweden, residing at New York, in the county of New York and State of New York, in the United States of America, have invented a new, original, and ornamental Design for a Body Plate for Electric Fixtures, of which the following is a specification, reference being had to the

accompanying drawing, forming part thereof.

Fig. 1 is a front view of a body plate for electric fixture, showing my new design.

Fig. 2 is a plan view of the same.

I claim:

The ornamental design for a body plate for electric fixtures, as shown.

THURE E. DAHL.
